UNITED STATES PATENT OFFICE.

HEINRICH BOCKISCH, DECEASED, LATE OF POUGHKEEPSIE, NEW YORK; BY GEORGE W. GITINS, ADMINISTRATOR, OF NEW YORK, ASSIGNOR TO WELTE-MIGNON CORPORATION, OF NEW YORK, N. Y., A CORPORATION OF NEW YORK.

AUTOMATIC MUSICAL INSTRUMENT.

Application filed April 21, 1920. Serial No. 375,575.

To all whom it may concern:

Be it known that HEINRICH BOCKISCH, deceased, late a citizen of the Republic of Czechoslovakia, and formerly residing at 5 Poughkeepsie, in the county of Dutchess and State of New York, United States of America, invented certain new and useful Improvements in Automatic Musical Instruments, of which the following is a specification.

This invention has relation to record-controlled musical instruments of the kind which comprise a plurality of sets or registers of tone elements, each set or register 10 having a quality of tone different from that of any other sets or registers; and the invention consists, broadly, of means of any suitable character operating under control of record-controlled impulses of different characteristics and selectively controlling the operations of a plurality of sets of tone elements, whereby a greater number of tonal effects may be controlled from a given width or area of record without any restriction in 15 respect of the individual operation of any of the tonal effects. The invention further consists in certain novel combinations and arrangements of element, and in certain peculiarities in the construction of parts, exemplified by the construction illustrated in 20 the accompanying drawings, said construction representing a preferred embodiment of the invention applied to the operation of a pipe organ, or the like, under control of a perforated note sheet or music roll.

It should be understood that the broad features of the invention may be applied to other musical instruments than those of the organ or orchestrion style, and also that it 25 may be variously organized to utilize impulses of correspondingly different nature, pneumatic or otherwise, and to be operated under control of other records than perforated note sheets or music rolls, and further 30 that, whatever the nature of the impulses or the nature of the record, selected by the individual constructor or designer, the mechanism may be embodied in various forms, without departing from the spirit of the invention. Nevertheless, it should also be understood that the invention has great utility 35 when embodied in an automatic musical instrument of the organ or orchestrion type for controlling the stop effects thereof, and 40 that the construction illustrated by the ac-

companying drawings has advantages of great importance for which reason it is not only preferred but has been made the subject of certain claims more and less defining the details thereof.

In other words, I would have it understood at the outset, that the invention is of fundamental nature with respect to the purposes which it accomplishes, and that those claims which are not expressly limited to 60 details of the illustrated embodiment are to be given the utmost breadth, having in mind the fundamental nature of the invention with respect to the purposes in view, namely with respect to the control of a plurality of 65 sets of tone elements forming part of a musical instrument, by means forming a common path for record-controlled impulses and which controls the sets through the intervention of connections which are of a selective nature.

It is of course understood that in the ordinary humanly played organ each set or register of tone elements, as pipes for example, is controlled by the opening and closing of a stop corresponding thereto, the opening of the stop rendering its set of tone elements operative and the closing of the stop rendering it inoperative. The tonal effects produced at a particular moment may 70 be said to be those which correspond to the keys which are struck and the particular stop or stops which are open at that moment, and a proper interpretation of the musical composition requires not only that the 75 proper keys shall be struck in proper succession and time, but also that the proper stops shall be opened in the various passages in the composition to produce the effects intended by the composer or to bring 80 out beauties in the composition which otherwise would be lost. In large organs there are many such stops and consequently many 85 different tonal effects at the command of the performer who possesses a developed musical instinct or nature and has been trained 90 to understand the effects which may be produced from proper use of the stops, individually and in the multiplicity of combinations in which they may be employed.

The aim, of course, in automatic musical instruments is to simulate human performance as nearly as possible. Perforated paper note sheets or music rolls constitute 95 the most commonly employed records for 100 105 110

operating such instruments. It is a well recognized fact that such records are very susceptible to climatic influences, and that they expand in a moist atmosphere and contract when dry, and that such contraction or expansion results in imperfect tracking and produces discords and improper operation. This susceptibility is increased with the width of the sheet or roll and hence there is a well recognized practical limit to the width of the sheet or roll, beyond which it should not extend, and, indeed, in any case it is important to reduce the width of the roll to the narrowest practical limit, having in mind the equally well recognized fact that there are limitations as to the closeness of the spacing of the tracker ducts from each other. Reduction of the size of the record to as compact an area as practicable is always important, regardless of the nature of such record, but is especially so when made of perforated paper as they now almost universally are. This invention, therefore, is not confined to perforated paper records, but is especially beneficial when such records are employed.

For example: In pneumatically operated mechanisms having a tractor bar whose ducts are opened and closed by perforations in a note sheet, it has been the custom in some cases to employ two ducts for each set of tone elements, one duct when opened admitting an atmosphere impulse to the mechanism to render the corresponding set of tone elements operative and the other duct when opened admitting a like impulse which operates the mechanism to again render said set of tone elements inoperative. In such case very few sets of tone elements could be embodied within the practical limits of the note sheet, for the reason that the space occupied by two lines of apertures is required for each set of tone elements. In other mechanisms the arrangement is such that one tracker duct serves for both of the foregoing operations, the arrangement being such that when the duct is opened the first time the corresponding set of tone elements are rendered operative and when the same duct is opened the second time they are rendered inoperative, and so on. The first arrangement practically limited the instrument to the use of twelve individually operable sets of tone elements under control of the record, while the second arrangement permits twenty-four such sets to be employed. The second arrangement thus removed some of the restrictions, as compared with the first arrangement, but nevertheless has not removed all restrictions for the reason that many organs include a greater number of sets of tone elements than can be practically handled individually even by the second arrangement, and it has been the custom in such cases to control the ad-

ditional stops as a unit so that they could not be used individually.

One of the very important purposes of the present invention is to overcome the foregoing restrictions by means of such nature that a plurality of sets of tone elements are controlled from a single tracker duct, or other means forming a path for an operating impulse or impulses, in such manner that either set is controllable individually, either being operable, alone or both together, as required in different portions of a musical composition.

In pursuance of this particular purpose of the present invention it includes a mechanism which is characterized, broadly, by the employment of an element which provides a path for record-controlled impulses having different characteristics and which element has connection with a plurality of mechanisms which respectively control the operation of the sets of tone elements and are of such nature that they are respectively controlled by said impulses and hence are selectively operated thereby. It will be understood that the control of the plurality of sets of tone elements by impulses of different characteristics transmitted to the respective operating mechanisms by a common element contemplates the impulses which render the tone elements operative as well as those which cut them out of operation. Accordingly, it will be seen that the width of the space required for the stop controls has been very substantially reduced, which is very important in any case, and in this particular exemplification of the invention enables all the sets of tone elements of even the largest organs to be operated individually, as well as in any desired combination thereof, within the limits practical for a record formed of perforated paper.

The operating impulses which I prefer are of pneumatic nature, and accordingly I have illustrated a mechanism which utilizes such impulses, the element over which the pneumatic impulses of different characteristics are transmitted being a duct such as is commonly used for the transmission of pneumatic impulses but having branches through which the impulses are transmitted to the plurality of controlling mechanisms or means to be operated from said duct. Moreover, it is preferred in practice to utilize impulses of a particular duration for one of the controlling means or mechanisms and impulses of a different duration for the other. The impulses of different duration constitute a species of impulses having different characteristics, of very beneficial nature. In any event, the controlling means are severally responsive functionally to the impulses having different characteristics, respectively. For example,

the controlling means for one set of tone elements would be operative by the shorter impulses and the controlling means for the other set would be operative by the longer impulses.

In the humanly played organ the performer manipulates the stops. In the record-played instruments of the class in which stop-effects are controlled by the record, it is not necessary that the mechanisms be arranged to operate the stops themselves to produce the effects. In other words, it is practicable to operate the control mechanism directly, i. e. without the intervention of the stops. The latter arrangement has been herein exemplified, although it is within the scope of the invention to so embody it that it will control the stop-effects from the record, through the medium of the stops themselves. Indeed, in a companion application executed by me of even date herewith (Serial No. 375,576, Patent No. 1,440,763,) there is illustrated, described and claimed a particular means of beneficial nature whereby the stops are moved under control of the record in the production of the various stop effects. It of course will be understood that the term "stops" as used herein apply to those elements which in practice are ordinarily mounted adjacent the front board of the manual case and are manipulated by hand to control the sets of tone elements, which latter also are sometimes called "stops." In the present application, the term "stop effects" when otherwise unqualified is intended to include thereunder those effects which in the humanly played organ are produced by the manipulating of the stops without restriction as to whether the stops are actually manipulated under control of the record. Moreover, in the illustrated type of ordinary organ there is a valve for each set or register of tone elements, each valve when opened admitting air under pressure to a wind passage to which a corresponding set of tone elements are connected. These valves in an organ may be defined as stop valves.

Having thus referred to some of the more important features of the invention and set forth the fundamental nature of the latter, I will now proceed to describe the illustrated embodiment thereof, and while I shall set forth this illustrated embodiment in minute detail this manifestly is without any intention of thereby restricting the invention to such details, or to a narrow range of equivalents thereof.

In said drawings, wherein like characters of reference denote corresponding parts in the several figures,

Figure 1 is a diagrammatic view, with certain parts in section and other parts broken away, illustrating an embodiment

of the invention applied to the operation of the stop valves in the wind chest of a pipe organ;

Fig. 2 is a detail view, partly in section, of the switching element embodied in the mechanism, with certain portions thereof omitted; and

Fig. 3 is a detail representation of part of a record of suitable construction to operate the mechanism.

For exemplary purposes only, there is illustrated a wind chest A provided with channels *a*, *a'*, having sets of pipes *b*, *b'* constituting tone elements emitting tones of different qualities as aeoline and French horn, respectively, said channels having ports 20, 21 through which they have communication with a pressure chamber *a*² and these ports being severally opened and closed by valves 22, 23, which valves together with their actuating means exemplify one form of devices which may be employed to control the respective sets of tone elements. In this particular type of organ, each channel also has a series of ports not shown—one for each pipe connected thereto and the latter ports are opened and closed by valves 24, of which valves all of those in a channel are connected with each other by a stem 25 so that they are operated simultaneously.

The construction thus far set forth is not substantially new and hence is not particularly claimed herein, in and of itself alone. It is to be regarded as being broadly illustrative of one embodiment in which there are appropriate devices for controlling the sets of tone elements, respectively, and also appropriate means by which the corresponding pipes of the several sets are controlled. It will be understood that the latter control in the ordinary organ is from the organ keys or pedals and in the record controlled organ is from the note perforations in the record. The said latter controls are not a part of the instant invention and are not further referred to herein: this invention having relation mainly to means under control of the record by which a plurality of suitable sets-controlling devices are operable under control of a single tracker—as a common duct in a pneumatic tracker, for example.

B designates a tracker board within which is the mouth 26 of a duct 27 which is common to the chambers *a* and *a'* of the wind chest A, said duct being connected with the valves 22 and 23, by mechanism of such nature as to control the operations of the valves to admit pressure to chambers *a*, *a'*, respectively.

To this end the duct 27 is provided with branches 28 and 29, one of which branches leads to a primary control member C and the other to a primary control member D. The control member C has a chamber 30 which is connected by a channel 31, with the

branch duct 28; a suction chamber 32, which is separated from the chamber 30 by a membrane 33 and has a bleed connection 34, 34^a to the branch duct 28; a chamber 35, having a suction port 36 through which it communicates with suction chamber 32 and also having an atmospheric port 37; a valve preferably composed of two valve-members 38 and 39, mounted on a stem 40 which is operatively related to the membrane 33, said valve being arranged in chamber 35 and operating to open suction port 36 and close atmospheric port 37, or to open said atmospheric port and close the suction port; and a primary circuit closing pneumatic 41 connected with chamber 35 by a channel 42. The movable board, 41^a, of the pneumatic 41 carries a contact element 43, for a purpose hereinafter explained.

10 The branch 29 of duct 27 opens into a chamber 44 in the primary control member D. This member has a suction chamber 45, which is separated from the chamber 44 by a membrane 46; a chamber 47 having a suction port 48 to chamber 45 and also having an atmospheric port 49; a valve 50 mounted in the chamber 47 and having its stem 51 operatively related to the membrane 46; and a channel 52 which opens into a second channel 53 having regulating screws 54 and 54^a and an atmospheric port 55. A duct 56 extends from the channel 53 to a primary circuit closing pneumatic 57 whose movable board 57^a is provided with a contact element 58 for a purpose hereinafter set forth.

15 When the duct 27 is opened air at atmospheric pressure is admitted through branch 28 to the chamber 30 in primary control member C and through branch 29 to the chamber 44 in primary control member D. The pressure thus imposed on the membrane 33 of primary control member C operates the valve members 38 and 39 to open suction port 36 and close atmospheric port 37. This places the interior of pneumatic 41 in communication with suction chamber 32 through port 36, chamber 35 and channel 42. Said pneumatic is thereby collapsed and its contact element 43 is thus brought into bridging relation with contact wires 59 and 60. An electrical circuit which includes a switch magnet 61 is thus closed, this circuit being as follows: from a suitable source of electrical potential indicated at 62, by way of the section 63 of a positive bus bar and wire 64 to contact wire 59, through contact element 43, and contact wire 60 and wire 65 to the positive terminal 66 of the magnet 61; through said magnet to the negative terminal 67 and back to the source 62 by way of wire 68. The energizing of the magnet causes it to attract its armature 69 and thus opens an atmospheric duct 70 which leads to a chamber 71 in a switching member E, the

armature 69, preferably having a surface of felt or other suitable material as shown to close the mouth of the duct 70 when the magnet is de-energized.

When air at atmospheric pressure is thus admitted to chamber 71, its pressure exerted upon a membrane 72 acts, through a valve stem 73, to operate a valve 74 to open a suction port 75 and close an atmospheric port 76, the valve 74 being mounted in a chamber 77 which is provided with said ports 75 and 76, the port 75 opening into a suction channel 78 and the port 76 opening into an atmospheric channel 79. A duct 80 extends from the chamber 77 to a pneumatic 81 and hence when the suction port 75 is opened the pneumatic 81 is collapsed, being now in communication with suction channel 78 through port 75, chamber 77 and duct 80. The movable board of the pneumatic 81 carries a valve actuator 82 which is pivoted thereto at 82^a and is provided with oppositely extending lateral projections 82^b having recesses forming seats to receive stop projections 82^c for a purpose hereinafter explained. When the pneumatic 81 is collapsed, the valve actuator is brought into engagement with either one of two atmospheric valves 83 or 84 according to the position to which it has been adjusted with relation to said valves in the manner hereinafter described. Its action upon the valve 83 is to admit air at atmospheric pressure to a chamber 85, which pressure is exerted upon a membrane 86 and thence to a valve stem 87 carrying a valve 88. This valve is mounted in a chamber 89 having a suction port 90, which opens into the suction channel 78, and also having an atmospheric port 91 which opens into the atmospheric channel 79. A duct 92 extends from a chamber 93 to the atmosphere and has its mouth in position to be closed by the valve 84. This duct has a branch 92^a extending to the chamber 89. The chamber 93 has a port 93^a extending to secondary circuit closing pneumatic 94 whose movable board is provided with a contact element 95, which bridges the space between two contact wires 96 and 97. These wires form parts of an electrical circuit which includes a stop magnet 98, this circuit being as follows: From the positive pole of the source 62, by sections 63, 99 and 100 of the positive bus bar, to wire 101 and thence to positive terminal 102 of magnet 98; through said magnet to the negative terminal 103 and by wire 104 to contact wire 96, and through said contact wire, the contact element 95 and contact wire 97 to a negative bus bar 105 and back to the source. It will thus be seen that when the valve 88 has been operated to open suction port 90 and close atmospheric port 91 the air in pneumatic 94 is attenuated, this pneumatic now being in communication with suction channel 78 through port 93^a, cham-

ber 93, duct 92, branch 92^a, chamber 89 and suction port 90. The pneumatic 94 is thus caused to collapse and close the circuit already traced through electro-magnet 98. 5 The closing of this circuit causes the magnet to attract its armature 106, thereby opening an atmospheric duct 107 and admitting air at atmospheric pressure to a chamber 108. The pressure of this air is exerted against a 10 membrane 109 which operates a valve 110 whose stem 111 is in operative relation with said membrane. This valve is mounted in a chamber 112 having a suction port 113 and an atmospheric port 114, and also having a 15 duct 115 which extends to a pneumatic stop-valve motor 116 whose movable board 116^a is connected with the stop valve 22 by a stem 117. The suction port 113 opens to a suction chamber 118 which is separated from 20 the atmospheric chamber 108 by the membrane 109. Hence, when magnet 98 is energized the pneumatic stop-valve motor 116 is collapsed, the interior of said motor being in communication with the suction channel 25 118, through duct 115, chamber 112 and port 113. It, accordingly, will be seen that when primary control duct 27 is opened, stop-valve 22 in the organ wind chest is opened, thus admitting pressure to channel *a* to cause any 30 of the pipes, *b*, connected to said channel to speak when the corresponding tone valves 24 are opened.

It has already been stated that when primary control duct 27 is opened air at 35 atmospheric pressure is admitted to chamber 44 of primary control member D simultaneously with the admission of air at said pressure to chamber 30 of primary control member C and it has been shown that the 40 admission of the atmospheric air to chamber 30 resulted in the closing of the circuit to switch magnet 61 and this in turn resulted in the opening of the stop valve 22 in the organ wind chest.

45 When air at atmospheric pressure is admitted to chamber 44, valve 50 is operated to open suction port 48 and close atmospheric port 49. This places the interior of the primary circuit closing pneumatic 57 under suction and if air is admitted to the chamber 44 for a sufficient length of time said pneumatic 57 will collapse sufficiently to carry its contact member 58 into bridging 50 relation with contact wires 118^a and 119^a 55 and will thereby close an electrical circuit which includes a switch magnet 120, this circuit being as follows: From the positive pole of the source 62 by way of sections 63 and 99 of the positive bus bar to wire 121; thence to contact wire 118^a and by contact element 58 and contact wire 119^a to wire 122; thence to the positive terminal 123 of the magnet 120 and through said magnet to the negative terminal 124 and 60 by wire 125 to the contact 126 on the nega-

tive bus bar 105 and thence back to the negative terminal of the source.

The energizing of this magnet causes it to attract its armature 127 and thereby opens an atmospheric duct 128 which extends to a chamber 129 in the switching member E. The armature 127 preferably has its surface adjacent the mouth of the duct 128 provided with a covering of soft material, as indicated. The pressure of the 70 atmospheric air thus admitted to the chamber 129 is exerted against a membrane 130 and as the opposite surface of said membrane is exposed to the minus pressure in the suction channel 78 it follows that the 75 membrane will be expanded and will exert pressure on the stem 131 of a valve 132 and will move said valve to open a suction port 133 and close an atmospheric port 134, said valve being arranged in a chamber 135 80 provided with such ports. A duct 136 extends from the chamber 135 to a pneumatic 85 137, so that said pneumatic is collapsed when the suction port 133 is opened. The movable board of this pneumatic carries a 90 valve actuator 138 one end of which is pivoted thereto at 138^a. This valve actuator opens either one of two valves 139, 140, according to its position when the pneumatic 95 is collapsed. It is provided with oppositely extending lateral projections 138^b having recesses forming seats to receive stop projections 138^c for a purpose hereinafter explained. Assuming that it is in position to open valve 139, it will be seen that its 100 105 operation will result in the admission of air at atmospheric pressure to a chamber 141, which air acts upon one surface of a membrane 142 whose opposite surface is exposed to the minus pressure in the suction channel 78. This membrane is operatively related to one end of the stem 143^a of a valve 143. Hence, when air at atmospheric pressure is admitted to chamber 141 by the opening of valve 139 the valve 143 will be moved 110 to open a suction port 144 and close an atmospheric port 145, this valve being arranged in a chamber 146 provided with said ports. This chamber (146) also has a connection, 147, to a duct, 148, one of whose 115 ends is in position to be closed by the valve 140 and the other of whose ends opens into the chamber 149. The chamber 149 has a duct 149^a through which it communicates with a secondary circuit closing pneumatic 150 whose movable board is provided with a contact element 151. It will thus be seen that when atmospheric valve 139 is opened, chamber 149 will be under suction and pneumatic 150 will collapse. This will cause 120 contact element 151 to engage contact wires 152 and 153 and will thereby close an electrical circuit which includes a stop-magnet 154, this circuit being as follows: from the 125 positive pole of the source 62, by way of 130

sections 63, 99 and 100 of the positive bus bar to wire 155; thence to the positive terminal 156 of the magnet, and through said magnet to the negative terminal 157; thence 5 by wire 158 to contact wire 152 and through the contact element 151 to contact wire 153 and thence by wire 159 to the terminal 160 on the negative bus bar 105 and back to the source.

10 The energizing of stop magnet 154 causes it to attract its armature 161 and thereby open to the atmosphere a duct 162 which extends to a chamber 163. The pressure of this air is exerted against a membrane 164 15 and causes said membrane to expand, the surface of the membrane opposite the chamber 164 being exposed to the minus pressure in a suction channel 165. When the membrane expands it acts upon a valve stem 166 20 to move a valve 167 to open a suction port 168 and close an atmospheric port 169, the valve being arranged in a chamber 170 provided with such ports. This chamber 170 also has a duct 171 through which it 25 communicates with the interior of a pneumatic stop-valve motor 172 whose movable board is connected with the stop valve 23 by a stem 173. It will thus be seen that when the 30 circuit to the stop magnet 154 is closed, motor 172 will collapse and open stop valve 23, thus admitting pressure to channel *a'* to cause any of the pipes *b'* connected thereto to speak when the corresponding valves 24 are opened.

35 Accordingly, it will be noted that the mechanism described includes means whereby the stop valves 22 and 23 may be opened and a control duct (27) common thereto has been described. The tendency 40 of course in said case is to operate both stop valves simultaneously and in order to overcome this tendency I have made provision for the closing of the circuit to the switch magnet 120 in a delayed or retarded relation 45 to the closing of the circuit to the switch magnet 61. This is exemplified in the illustrated embodiment of the invention by making the primary switch closing pneumatic (57) of the primary control member D of a 50 larger size than the primary switch closing pneumatic (41) of the member C, it being apparent that when two pneumatics of different sizes are subjected to forces of similar strength the larger one will require 55 more time to collapse it than will the smaller one, as its movable board will have to traverse a greater distance. To further regulate the period of time the regulating screws 54 and 54^a are provided, one of said 60 screws controlling communication between the channel 53 and the chamber 47 and the other between said channel and the atmosphere, the arrangement of the screws being thus such that they conjointly provide for 65 an adjustable regulation of the tension of

the air in the channel 53 and consequently in the pneumatic 57 to a degree of great nicety.

It is manifest that the mechanism thus far illustrated and described is of nature 70 such that stop valve 22 may be opened without opening the stop valve 23, merely by closing the primary control duct 27 before primary control pneumatic 57 has collapsed sufficiently to close the circuit to the switch 75 magnet 120, and that when it is desired to open both valves it is necessary only to keep the control duct 27 open until pneumatic 57 has been fully collapsed.

It is manifest that each of said valves 22 80 and 23 would close immediately upon the cessation of the impulse which initiated its opening movement, unless provision is made for maintaining it in open position throughout the entire period the corresponding set 85 of tone elements are to be affected thereby. In order to meet this condition, I have so organized the mechanism that each valve 22, 23 is opened and closed by successive 90 impulses of the characteristics to which its operative means are responsive, and, hence, remains open during the interim between such impulses.

Certain of the elements of the connections 95 to the respective stop valves 22, 23 by which this important result is secured, have already been set forth, to wit, the pneumatics 81 and 137, valve actuators 82 and 138 and the pairs of valves 83, 84 and 139, 140, and the elements which in the illustrated embodiment are co-ordinated therewith to open and close each of the valves 22, 23 by successive impulses of the characteristics to which its operating means are functionally responsive will now be set 105 forth.

The stem 87 of the valve 88, which valve is included in the connection to stop valve 22, is in operative relation with a membrane 175 which is arranged between the chamber 93 and the atmospheric channel 79 and said chamber 93 is connected by a port 178 with a pneumatic 176 whose movable board is connected with the valve actuator 82 by a link 177. 110

Similarly, the stem 143^a of the valve 143 in the connection to the stop valve 23 is in operative relation with a membrane 142^a which is arranged between the chamber 149 and an atmospheric channel 79^a and said chamber 149 is connected by a port 149^b with a pneumatic 180 whose movable board is connected to the valve actuator 138 by a link 181. 115

It will be noted that the pneumatics 176 and 180 with their links 177 and 181 constitute means for oscillating the respective arms 82 and 138, the co-ordination of the parts being such that as soon as stop valve 22, or stop valve 23, has been opened, 120

and the opening 26 closed, the pneumatics 81 and 176, or the pneumatics 137 and 180, corresponding to the opened valve 22 or 23, become effective to move the corresponding 5 arm 82 or 138 longitudinally and to shift the same laterally, the longitudinal movement of the arm at this time being in a direction such that the pressure exerted by the arm on valve 83 or 139, according to 10 which arm is moved, is discontinued and the co-acting locking projections 82^b, 82^c or 138^b, 138^c, at the left hand side of the arm are free from each other, so that the pneumatic 176, or 180, which is still connected to 15 the exhaust channel 78 by reason of the pressure maintained on the membrane 175 or 142^a, becomes effective to shift the arm toward the right and into line with the valve 84 or valve 140.

20 This longitudinal movement of arm 82, or arm 138, is manifestly the result of the closing of the duct 27. It should be noted, however, that valve 88, or 143, is not closed as a consequence of the closure of valve 83, 25 or 139, being maintained in its open position by the preponderating pressure exerted on the membrane 175, or 142^a. In other words, the closing of valve 83, or 139, in so far as its action on valve 88, or 143, is concerned, being merely to cut off communication of corresponding chamber 85, or 141, with the atmosphere so that the pneumatic tensions on opposite sides of membrane 86, or 142, gradually counterbalance each other, 30 the tension of the air in the corresponding chamber 93, or 149, remaining unchanged until valve 84, or 140 has been opened. The opening of valve 84, or 140, occurs when the duct 27 is again opened, the arm 82, or 138 35 having meanwhile, as already stated been shifted laterally into line with said valve 83, or 140, it being, of course, understood that when the duct 27 is opened this (second) time, magnet 61, or 120, according to 40 45 the duration of the impulse admitted to said duct, will be energized, valve 74, or 132, will again be raised, pneumatic 81 or 137 will again be collapsed, and arm 82, or 138, will be moved to open valve 84, or 140, thereby 50 admitting air at atmospheric pressure to chamber 89, or 146, and permitting valve 88, or 143, to fall. The air at atmospheric pressure thus admitted to chamber 93, or 55 149, permits pneumatic 94 or 150 to expand and break the circuit to magnet 98, or 154, and also tends to expand pneumatics 177, or 180. When the impulse which initiated this operation ceases, valve 74, or 132, will fall, pneumatic 81, or 137, will again be expanded, thereby removing the pressure imposed by the arm 81, or 138, upon valve 84, or 140, (allowing the latter valve to be closed by its spring) and freeing the right hand projection 81^b, or 138^b of said arm, 60 65 from its engagement with the corresponding

stop projection 81^c, or 138^c, thereby allowing pneumatic 176, or 180, (which has been restrained by the engagement of said locking projections 81^b and 81^c, or 138^b and 138^c with each other, from acting until said locking projections have been disengaged) 70 to act to shift the arm, 81 or 138 laterally into line with valve 83, or 139.

Accordingly, it follows that switch pneumatic 94 remains collapsed during the interim between two successive impulses of a nature to which the switch pneumatic 41 is functionally responsive and that switch pneumatic 150 similarly remains collapsed during the interim between two successive 80 impulses of a nature to which the switch pneumatic 57 is functionally responsive: and it will be manifest that during such intervals, respectively, the circuits to the magnets 98 and 154, will be closed and corresponding pneumatics 116 and 172 will remain collapsed.

A statement of the various phases of operation is as follows:

In Fig. 1 all the parts are shown in the 90 positions they occupy when both stop valves 22 and 23 are closed, as at the beginning of the operation, for example.

If now an impulse of air be admitted to duct 27, the following operations will take 95 place, if said impulse be a short one, namely, primary circuit closing pneumatic 41 will collapse and close the circuit to switch magnet 61 and this in turn will cause valve 74 to open, thereby causing pneumatic 81 to 100 collapse and move valve actuator 82 to open valve 83, thereby causing valve 88 to open suction port 90 and close atmospheric port 91, whereupon the air in chamber 93 is rarefied. This causes the secondary circuit 105 closing pneumatic 94 to collapse, thus closing the circuit to stop magnet 98 and causing the stop pneumatic 116 to collapse and open stop valve 22.

The rarefaction of the air in the chamber 93 also tends to collapse pneumatic 176 but this tendency is resisted by the engagement of the projection 82^b at the left hand side of the valve actuator with the corresponding projection 82^c, it being noted 110 that an effective engagement of these projections has been completed at the time the valve 83 is opened.

All the foregoing operations should be 115 quickly accomplished and the means illustrated are of such nature that they take place substantially instantaneously.

As soon as valve 22 has been opened, duct 120 125 130 135 140 145 150 155 160 165 170 175 180 185 190 195 200 205 210 215 220 225 230 235 240 245 250 255 260 265 270 275 280 285 290 295 300 305 310 81 is expanded by its spring and withdraws the valve actuator out of locking engagement with projection 82^c and out of pressure-imposing engagement with valve 83 and the latter valve closes. However, valve 88 is open and 84 is closed at this time, being held in this position by pressure on membrane 175 and accordingly the air in chamber 93 will still be rarefied so that 10 secondary pneumatic 94 remains collapsed and the circuit to stop magnet 98 will not be broken and the valve 22 will not be closed. Moreover, the withdrawal of the valve actuator from locking engagement 15 with the stop 82^c permits pneumatic 176 to collapse and to shift valve actuator 82 pivotally into such position that its next movement will cause it to open valve 84: in other words the lateral shifting of the valve actuator 82 occurs when duct 27 has been 20 closed but before it is again opened.

When it is desired to discontinue the quality of tone effected when channel *a* is open, duct 27 is again opened. This results in the closing of the circuit to switch magnet 61 which in turn results in the opening of valve 74 and the collapsing of pneumatic 81. This causes the actuator 82 to open valve 84 and engages the right hand 30 projection 82^b with the corresponding stop projection 82^c. The opening of valve 84 admits air at atmospheric pressure to chamber 93 and accordingly brings about a balancing of the pressures on opposite sides of 35 the membrane 175 and releases the valve 88 which now closes the suction duct 90 and opens the atmospheric duct 91. The secondary switch pneumatic 94 is expanded by its spring, thus breaking the circuit to stop 40 magnet 98 and this, in turn, results in the closing of duct 107, the closing of suction port 113 and opening of atmospheric port 114 and the expansion of pneumatic 116 by its spring and the closing of the valve 22. 45 Duct 27 is again closed, whereupon the circuit to magnet 61 is again broken, duct 70 is closed, valve 74 is again moved to open chamber 77 to atmospheric port 76 and close suction port 75, and pneumatic 81 is expanded, thus moving the valve actuator 82 until its pressure upon the valve 84 is released and said valve is permitted to be closed by its spring. During this movement 50 of the actuator, it is released from the right hand stop projection 82^c whereupon the pneumatic 176 becomes effective to shift the actuator into line with the valve 83, this shifting movement of the actuator being completed by the time the valve 84 is 55 closed.

It will be apparent that if the duct 27, after being opened, is closed before the impulse admitted therethrough has been of sufficient duration to collapse the slow acting pneumatic 57 the stop valve 22 will be

opened but stop valve 23 will not be opened. Accordingly, it will be seen that by closing the duct 27 as soon as valve 22 is opened any of the tone elements *b* may be caused to speak until said duct 27 is again opened, and that during this time the corresponding tone elements *b'* will remain silent. 70

If, on the other hand, it is desired to open the valve 23 and to permit the tone elements *b'* to speak alone, i. e. without the corresponding tone elements *b*, it is only necessary to open the duct 27, close it quickly, and again open it and allow it to remain open until switch pneumatic 57 has fully collapsed, it being remembered that valve 21 is 75 opened and closed by successive impulses and that the tones affected by the opening of said valves are those which are sounded in the interval between such successive impulses. The second opening of the duct 27 thus acting to close the valve 22 will, being continued, also cause valve 23 to be opened, as follows:—

It will collapse pneumatic 57 and this in turn will cause the circuit to magnet 120 to be completed, thus opening atmospheric duct 128 and causing valve 132 to move and open suction port 133 and close atmospheric port 134, thereby collapsing pneumatic 137 and causing it to move valve actuator 138 to open valve 139; thus causing valve 143 to move and open suction port 144 and close atmospheric port 145; thus, in turn, placing chamber 149 under suction and causing the secondary switch pneumatic 150 to collapse, thereby closing the circuit to stop magnet 154, which being thus energized causes air at atmospheric pressure to be admitted to chamber 163, thus moving valve 167 and causing it to open suction port 168 and close atmospheric port 169, whereupon the pneumatic 172 is collapsed and acts to open valve 23. When this has been accomplished, duct 27 may be closed, the valve 23 remaining open until said duct is again opened, it being noted that the chamber 149 will remain under suction owing to the pressure exerted on membrane 142^a, and accordingly that the circuit to magnet 154 will remain closed until valve 140 has been opened. During this closed period of the duct 27, i. e. before the duct is again opened, valve 23 is held in open position and channel *a* is under pressure adequate to cause any of the tone elements *b'* to speak when the corresponding valves 24, are opened. 110

The following operation takes place as soon as duct 27 has been closed, namely:

Pneumatic 57 is expanded by its spring, 125 breaking the circuit to magnet 120 which being thus deenergized permits its armature to again close duct 128. Valve 132 now moves to close suction port 133 and open atmospheric port 134, this operation being expedited by the provision of a bleed hole 130

129^a between chamber 129 and suction chamber 78. Air at atmospheric pressure is thus admitted to the pneumatic 137, and the spring of said pneumatic causes the pneumatic 5 to expand, thus releasing valve 139 from the pressure exerted thereon by the valve actuator 138 and permitting said valve to close.

During this movement of the actuator 138 it is shifted pivotally toward the right hand by the collapsing of the pneumatic 180; the tendency of this pneumatic to collapse as soon as valve 143 is moved to open, communication of chamber 149 with suction channel 78; i. e. when valve 139 was opened, having been resisted by the engagement of the left hand projection 138^b from the valve actuator with stop projection 138^c. When the valve actuator 138 has been shifted toward the right hand it is in position to open valve 140 upon its next movement. This occurs when pneumatic 57 is again collapsed, thereby energizing magnet 120, causing valve 132 to open suction port 133 and close atmospheric port 134, thus again placing pneumatic 137 under suction and causing it to collapse and move the valve actuator. The valve actuator being at this time in line with valve 140, opens the latter, thus admitting air at atmospheric pressure to chamber 149 through the duct 148. Up until this moment valve 143 was held by pressure on the membrane 142^a in the position to which it had been moved in the previous operation, namely, that position in which the suction port was opened and atmospheric port 145 closed, at which time chamber 149 is under suction, so that the pressure in chamber 79^a is the predominating force and by its exertion upon membrane 142^a holds the valve in the position stated.

Accordingly, it follows that when chamber 149 is opened to the atmosphere by the opening of valve 140, valve 143 is released as there is now a counterbalancing of pneumatic pressures on opposite sides of membrane 142^a and similarly a counterbalancing of suctional forces on opposite sides of membrane 142. Valve 143 immediately closes the suction port 144 and opens atmospheric port 145.

The interior of the secondary switch pneumatic 150 being now in communication with the atmosphere is expanded by its spring, thus breaking the circuit to magnet 154 which being thus de-energized closes duct 162 thereby cutting off communication of chamber 163 with the atmosphere and permitting valve 167 to move and close suction port 168 and open atmospheric port 169, thereby admitting air at atmospheric pressure to the interior of pneumatic 172 which thereupon is expanded by its spring, thus closing valve 23.

It will be apparent that if the valve 23

is to be closed without at the same time introducing pressure into channel *a* to render the tone elements *b* operative, the duct 27 must be opened momentarily immediately in advance of that opening of the duct which is to collapse the pneumatic 57, this preliminary momentary opening of the duct acting to set the parts which control the valve 22 in such position that when the duct 27 is opened the second time, for a period sufficient to collapse pneumatic 57, said parts connected to the valve 22 will close the latter and cause it to remain closed throughout the period required to collapse pneumatic 57.

On the other hand if it be desired to cut off the pressure to channel *a'* and at the same time open channel *a* to pressure adequate to operate the tone elements *b* the admission of the preliminary impulse is omitted, an impulse of sufficient duration to collapse the pneumatic 57 being all that is required to set into action the means which open valve 22 when said valve is closed, as well as to close valve 23 when the latter is open. Moreover, if both valves are closed a single long impulse admitted to duct 27 will open both.

In short, in the operation of the mechanism herein exemplified: (1) a single short impulse admitted to duct 27 when both valves 22 and 23 are closed followed after an interval by another short impulse, will open valve 22 without opening valve 23 and will keep said valve 22 open throughout the period between the two impulses, thereby introducing into channel *a* pressure adequate to operate any of the tone elements *b* without introducing pressure into channel *a'*; (2) a short impulse introduced into the duct 27 when valves 22 and 23 are closed immediately followed by a long impulse will open the channel *a'* to pressure adequate to operate any of the tone elements *b'* without at the same time opening channel *a* to pressure for a sufficient length of time to operate any of the tone elements *b*; (3) a single long impulse introduced into duct 27, when both valves are closed, will open both of said valves, and thereby admit to both channels *a* and *a'* pressure adequate to operate any of the tone elements *b* and *b'* when the corresponding valves 24 are opened; (4) a single short impulse introduced into duct 27 when valve 22 is open and valve 23 closed will close said valve 22 without opening valve 23; (5) a single short impulse introduced into duct 27 when valve 22 is closed and valve 23 is opened if quickly followed by a long impulse will close valve 23 and while in this operation valve 22 will be opened for an instant it will be again closed before any of the tone elements *b* are operated, the effect thus being to exclude tone elements *b'* without rendering the tone elements *b* operative; (6) a single long impulse introduced into duct 27 when valve 22 is closed and valve 23

110
115
120

130

is opened will result in the opening of valve 22 and the closing of valve 23.

In Fig. 3 I have illustrated a preferred means for opening and closing the duct 27. It will be apparent that this means contemplates openings α to α^6 , inclusive, in the perforated note sheet X which constitutes the record for opening the valves 24, as well. I have not considered it to be necessary to illustrate the perforations for opening the valves 24 by introducing air impulses to the tracker ducts b^2 as this part of the mechanism is well known. In this figure I have exemplified an arrangement of perforations such that (assuming that both valves 22 and 23 are closed at the beginning of the operation and that the record is fed in the direction of the arrow) perforation α will admit a short impulse of air to duct 27, and this will open valve 22 without opening valve 23, the result being that if any of the valves 24 be now opened, the corresponding tone-elements b will speak (while the corresponding tone elements b' will remain silent) until perforation α' has been brought into registration with duct 27, at which moment another quick impulse of air is admitted to duct 27 whereupon valve 22 is immediately closed: none of the tone elements b or b' now speak until perforation α^2 is brought into registration with duct 27, whereupon a quick impulse of air is admitted to duct 27, but this quick impulse is immediately succeeded by a long impulse brought about by the movement of the long perforation α^3 in registration with the duct 27: this results first in the closing of valve 22, which was opened by the short impulse, and then in the opening of valve 23: the valves remain in these positions, respectively, until perforation α^4 has been brought into registration with duct 27: this admits a short impulse to duct 27 sufficient to open valve 22 but being immediately succeeded by the registration of long perforation α^5 with said duct admitting a long impulse to the latter, valve 22 is closed before any of the tone elements b have had an opportunity to speak, the first portion of the impulse closing valve 22 and said impulse continuing for a sufficient length of time to close valve 23, the result being that during the interim between the time when perforation α^3 passes out of registration with duct 27 and perforation α^5 also passes out of registration with said duct, channel a' will be under pressure and only the tone elements b' which correspond with valves 24 which are opened at this time will speak: both valves 22 and 23 being now closed, none of the tone elements b or b' will speak even though tone valves 24 be opened. If a long perforation, as α^6 , be now brought into registration with duct 27, to admit a long impulse thereto, valve 22 will first be

opened and valve 23 will then be opened, with the result that tone elements b and b' , corresponding to any valve 24 which is now opened, will speak. Another long perforation, as α^7 , will close both of said valves 22 and 23. Of course, it will be understood that this is merely exemplary and that in practice the perforations will be variously arranged, i. e. arranged in the particular order or sequence as to spacing and lengths, required by the musical composition being rendered.

It will also be understood that while I prefer to utilize air impulses as the means for initiating the operation of opening and closing the valves 22 and 23 yet I am aware that there are other impulses than those of a pneumatic nature which may be utilized and accordingly my invention in its broadest aspects is not restricted to an embodiment designed to utilize pneumatic impulses, and on the contrary contemplates the utilization of impulses of any suitable nature, with such modifications or changes as are applicable thereto. Moreover, the term "impulses" is used in a generic sense and the terms "long" and "short" are to be regarded as being relative or comparative terms and not as defining any special lengths as this obviously will depend upon the sensitiveness of the mechanism. Again, while I prefer to employ a perforated record as the means for controlling the impulses, I am aware that records of other nature may be employed. Furthermore, I want it understood that while I have illustrated and described an embodiment of the invention preferred when it is to be utilized as a means for controlling the operations of a plurality of sets of organ pipes for example, yet I fully recognize the fact that the invention may be employed in musical instruments of other kinds than organs or the like, and particularly that it may be employed in any musical instrument having tone elements of whatever nature which are divisible into groups or sets, which groups or sets are to be controlled as groups or sets, as contradistinguished from the control of individual tone elements within groups or sets.

In short, while I have illustrated one embodiment and application of the invention I would have it understood that this is merely exemplary and that the invention may be otherwise and variously embodied and otherwise and variously applied in and with relation to musical instruments generally for controlling musical effects, tonal or otherwise, without departing from its spirit and the scope of appended claims.

Having thus described the invention what is believed to be new and is desired to be secured by Letters Patent, is:

1. In a record controlled musical instrument, a plurality of sets of tone elements,

1 a plurality of control means therefor, and mechanism to operate the control means, including means providing a common path for record controlled impulses of different 5 characteristics, and members which are functionally responsive to said impulses, respectively, and are controlled thereby to operate said control means severally, to render operative either of the sets of tone elements 10 alone under control of a record.

2. In a record controlled musical instrument, a plurality of sets of tone elements, a plurality of control means therefor, and means independent of any manually operable 15 means to operate the control means to render operative either of the sets of tone elements alone or both together, wholly under control of a record, said operating means including members which are functionally responsive to record controlled impulses 20 of different characteristics, respectively, and means providing a common path for said impulses.

3. In a record controlled musical instrument, a plurality of sets of tone elements, a plurality of control means therefor, and mechanism independent of any manually operable means to operate the control means to render operative either of the sets of tone 30 elements alone under control of a record, said mechanism including means providing a common path for record controlled impulses of different characteristics, control members having connection with said 35 means, and operative connections between said members and the first mentioned control means, including members which are functionally responsive to impulses of different characteristics, respectively.

40 4. In a record controlled musical instrument, a plurality of sets of tone elements, a plurality of control means therefor, and means to operate the control means to render operative either of the sets of tone elements alone, or both together, under control 45 of a record, said operating means including control members and elements which are controlled thereby and are functionally responsive to record-controlled impulses of different characteristics, respectively, and means providing a common path for said impulses, having branches for leading the impulses to the respective control members.

5. In an automatic musical instrument, 55 mechanism for controlling the operations of a plurality of sets of tone elements, including means providing a common path for record controlled impulses of different characteristics, means functionally responsive to the impulses of different characteristics, respectively, and connections controlled by the latter means to render either set of tone elements operative alone or both sets operative together.

65 6. In an automatic musical instrument,

mechanism for controlling the operations of a plurality of sets of tone elements, including means providing a common path for record controlled impulses of different lengths, respectively, circuit making and 70 breaking means functionally responsive to said impulses respectively, and connections including electrical circuits between said circuit making and breaking means and the sets of tone elements, respectively. 75

7. In an automatic musical instrument, mechanism for controlling the operations of a plurality of sets of tone elements, including means providing a common path for record controlled pneumatic impulses of 80 different characteristics, respectively, a plurality of pneumatics functionally responsive to the impulses of different characteristics, respectively, and control connections between the pneumatic and the sets of 85 tone elements, respectively.

8. In an automatic musical instrument, mechanism for controlling the operations of a plurality of sets of tone elements, including means providing a common path for record controlled pneumatic impulses of 90 different lengths, respectively, relatively quick and slow acting pneumatics controlled by the impulses of different lengths, respectively, and control connections between the pneumatics and the sets of tone elements, respectively. 95

9. In an automatic musical instrument, mechanism for controlling the operations of a plurality of sets of tone elements, including means providing a common path for record controlled pneumatic impulses of 100 different lengths, respectively, pneumatically operable circuit making and breaking means functionally responsive to the impulses of different lengths respectively, and connections including electrical circuits between said circuit making and breaking means and the sets of tone elements, respectively. 105

10. In an automatic musical instrument, a plurality of sets of tone elements, means providing a common path for record-controlled impulses of different characteristics, separate power means functionally responsive to the impulses of different characteristics, respectively, circuit making and breaking means controlled by the power means, respectively, and operating connections between the circuit making and breaking means and the sets of tone elements; including electrical circuits, respectively, controlled by the circuit and breaking means. 110 115

11. In an automatic musical instrument, a plurality of sets of tone elements, a plurality of devices for controlling the operations of the sets, respectively, means providing a common path for record controlled pneumatic impulses of different 120 125

130

- lengths, separate power means functionally responsive to the impulses of different lengths, respectively, and connections between the latter means and the sets controlling devices, respectively. 16. In an automatic musical instrument, a plurality of sets of tone elements, and control mechanism therefor, including means providing a common path for record controlled impulses of different characteristics and connections between said means and the respective sets of tone elements, said connections being independent of any manually operable means and having elements which are respectively responsive functionally to the impulses of different characteristics and are operated under control of successive impulses to render the corresponding set of tone elements operative and non-operative, whereby their operative condition is maintained during the interim between the successive impulses of the characteristics to which said elements are respectively responsive. 65 70 75 80 85 90 95 100 105 110 115 120 125
12. In an automatic musical instrument, a plurality of sets of tone elements, a plurality of devices for controlling the operations of the sets of tone elements, respectively, means providing a common path for record controlled impulses of different characteristics, separate power means functionally responsive to the impulses of different characteristics, respectively circuit making and breaking means, and connections between the circuit making and breaking means and the sets controlling devices, said connections including electrical circuits respectively controlled by the circuit making and breaking means. 13. In an automatic musical instrument, a plurality of sets of tone elements, a plurality of devices for controlling the operations of the sets of tone elements, respectively, means providing a common path for record controlled pneumatic impulses of different characteristics, a plurality of pneumatically operable power means functionally responsive, respectively to the impulses of different characteristics, and connections between the latter means and the sets controlling devices, circuit making and breaking means and connections including electrical circuits respectively controlled by the circuit making and breaking means. 14. In an automatic musical instrument, a plurality of sets of tone elements, a plurality of devices for controlling the operations of the sets of tone elements, respectively, means providing a common path for record controlled impulses of different characteristics, pneumatics functionally responsive to the impulses of different characteristics, respectively, and connections between the pneumatics and the sets controlling devices, said connections including electrical circuits respectively controlled by the pneumatics. 15. In an automatic musical instrument, a plurality of sets of tone elements, a plurality of devices for controlling the operations of the sets of tone elements, respectively, means providing a common path for record controlled pneumatic impulses of different characteristics, a plurality of pneumatically operable circuit making and breaking means functionally responsive to the impulses of different characteristics, respectively, and having separate operative connections for said impulses and connections between the latter means and the sets controlling devices, including electrical circuits respectively controlled by the circuit making and breaking means. 17. In an automatic musical instrument, a plurality of sets of tone elements, means providing a common path for record controlled impulses of different characteristics, control means functionally responsive to the impulses of different characteristics respectively and connections between the latter means and the sets of tone elements, respectively, including elements to render the tone elements operative and non-operative under control of successive impulses of a nature to which the respective control means are functionally responsive. 18. In an automatic musical instrument, a plurality of sets of tone elements, means providing a common path for record controlled pneumatic impulses of different characteristics, control means functionally responsive to the impulses of different characteristics respectively and connections between the latter means and the sets of tone elements, respectively, including elements to render the tone elements operative and non-operative under control of successive impulses of a nature to which the respective control means are functionally responsive. 19. In an automatic musical instrument, a plurality of sets of tone elements, means providing a common path for record controlled impulses of long and short duration, control means functionally responsive to the impulses of long and short duration, respectively, and connections between the control means and the sets of tone elements, respectively, including elements to render the tone elements operative and non-operative under control of successive impulses of a nature to which the respective control means are functionally responsive. 20. In an automatic musical instrument, a plurality of sets of tone elements, means providing a common path for record controlled pneumatic impulses of long and short duration, control means functionally responsive to the impulses of long and short dura-

- tion, respectively and connections between the control means and the sets of tone elements, respectively, including elements to render the tone elements operative and non-operative under control of successive impulses of a nature to which the respective control means are functionally responsive. 5
21. In an automatic musical instrument, a plurality of sets of tone elements, means 10 providing a common path for record controlled impulses of long and short duration, circuit making and breaking pneumatics functionally responsive to the impulses of long and short duration, respectively, and 15 means controlled by said pneumatics and controlling the sets of tone elements, respectively, including elements by which the respective sets of tone elements are rendered operative and non-operative by successive 20 operations of the pneumatics.
22. In an automatic musical instrument, a plurality of sets of tone elements, means providing a common path for record controlled impulses of different characteristics, control 25 means functionally responsive to the impulses of different characteristics, respectively, sets controlling devices, and connections between the latter means and the sets controlling devices, each connection including 30 means to operate its set controlling device to make the corresponding set of tone elements operative and non-operative, respectively, by successive operations of said control means.
23. In an automatic musical instrument, a plurality of sets of tone elements, means providing a common path for record controlled impulses of different characteristics, control 35 means functionally responsive to the impulses of different characteristics, respectively, sets controlling devices, and connections between the latter means and the sets controlling devices, each connection including 40 means to operate its set controlling device to make the corresponding set of tone elements operative and non-operative, respectively, by successive operations of said control means, comprising an oscillating 45 member and means controlling the oscillating member at the end of the opening operation to make the corresponding set of tone elements operative and non-operative, respectively, by successive operations of said control means, comprising an oscillating member and means controlling the oscillating member at the end of the opening operation to place it in position for the closing operation and at the end of the closing operation to place it in position for the opening operation. 50
24. In an automatic musical instrument, a plurality of sets of tone elements, means providing a common path for record controlled impulses of different characteristics, control 55 means functionally responsive to the impulses of different characteristics, respectively, sets controlling devices and connections between the latter means and the sets controlling devices, each connection including 60 means to operate its set controlling device to make the corresponding set of tone elements operative and non-operative, respectively, by successive operations of said control means, comprising a member mounted 65 for longitudinal and oscillatory move- 130
- elements operative and non-operative, respectively, by successive operations of said control means, comprising an oscillating member and yielding means controlling the oscillating member at the end of the opening operation to place it in position for the closing operation and at the end of the closing operation to place it in position for the opening operation. 70
25. In an automatic musical instrument, a plurality of sets of tone elements, means providing a common path for record controlled impulses of different characteristics, control 75 means functionally responsive to the impulses of different characteristics respectively, sets controlling devices and connections between the latter means and the sets controlling devices, each connection including 80 means to operate its set controlling device to make the corresponding set of tone elements operative and non-operative, respectively, by successive operation of said control means, comprising a pneumatically moved oscillating member and means controlling the oscillating member at the end 85 of the opening operation to place it in position for the closing operation and at the end of the closing operation to place it in position for the opening operation. 90
26. In an automatic musical instrument, a plurality of sets of tone elements, means providing a common path for record controlled impulses of different characteristics, control 95 means functionally responsive to the impulses of different characteristics, respectively, sets controlling devices and connections between the latter means and the sets controlling devices, each connection including 100 means to operate its set controlling device to make the corresponding set of tone elements operative and non-operative, respectively, by successive operations of said control means, comprising a circuit making and breaking means, a pneumatically moved oscillating member and means controlling 105 the oscillating member at the end of the opening operation to place it in position for the closing operation and at the end of the closing operation to place it in position for the opening operation. 110
27. In an automatic musical instrument, a plurality of sets of tone elements, means providing a common path for record controlled impulses of different characteristics, control 115 means functionally responsive to the impulses of different characteristics, respectively, sets controlling devices, and connections between the latter means and the sets controlling devices, each connection including 120 means to operate its set controlling device to make the corresponding set of tone elements operative and non-operative, respectively, by successive operations of said control means, comprising a member mounted 125 for longitudinal and oscillatory move-

ment, a pneumatic for moving the member, and yielding means controlling the same at the end of the opening operation to place it in position for the closing operation and at 5 the end of the closing operation to place it in position for the opening operation.

28. In an automatic musical instrument, mechanism for controlling the operations of a plurality of sets of tone elements, including 10 means providing a common path for record controlled pneumatic impulses of different characteristics, pneumatically operable means functionally responsive to the impulses of different characteristics, respectively, and control connections between the latter means and the sets of tone elements, respectively, each connection having means by which it is rendered operative and non-operative respectively with relation to the 15 corresponding set of tone elements by successive operations of the corresponding pneumatically operable means.

29. In an automatic musical instrument, a plurality of sets of tone elements, means 25 providing a common path for record controlled impulses of different characteristics, and mechanism to put either or both of the sets of tone elements into and out of action severally, including control members functionally responsive to record controlled impulses of different characteristics, respectively, and connections between said control members and the corresponding sets of tone elements, each connection having means by 30 which the corresponding set of tone elements is rendered operative and non-operative by successive impulses of a characteristic to which the corresponding control member is functionally responsive.

40 30. In an automatic musical instrument, a set of tone elements, means providing a path for record controlled impulses, and connections to the set of tone elements, controlled by the impulses, said connections including 45 a valve, means for alternately opening and closing the same by successive impulses transmitted over the same path and including a control valve for effecting the opening movement and a second control valve for effecting the closing movement.

31. In an automatic musical instrument, a set of tone elements, means providing a path for record controlled impulses, and connections to the set of tone elements, controlled 55 by the impulses, said connection including a valve, means for alternately opening and closing the same by successive impulses and including a valve for effecting the opening movement, a second control valve for effecting the closing movement and a single member for alternately engaging the control valves.

60 32. In an automatic musical instrument, a set of tone elements, means providing a path 65 for record controlled impulses, and connec-

tions to the set of tone elements, controlled by the impulses, said connections including a valve, means for alternately opening and closing the same by successive impulses and including a valve for effecting the opening 70 movement, a second control valve for effecting the closing movement, a single member for alternately engaging the control valves and pneumatic means for moving said single member.

75 33. In an automatic musical instrument, a set of tone elements, means providing a path for record controlled impulses, and connections to the set of tone elements, controlled by the impulses, said connections including a valve, means for alternately opening and closing the same by successive impulses and including a valve for effecting the opening movement, a second control valve for effecting the closing movement, a single member for alternately engaging the control valves, pneumatic means for moving said single member and a valve controlling the movement of the single member for opening the control valves.

80 34. In an automatic musical instrument, a set of tone elements, means providing a path for record controlled impulses, and connections to the set of tone elements, controlled by the impulses, said connections including a valve, means for alternately opening and closing the same by successive impulses and including a valve for effecting the opening movement, a second control valve for effecting the closing movement, a single member for alternately engaging the control valves, pneumatic means for moving said single member, a valve controlling the movement of the single member for opening the control valves, and electromagnetic 85 means for controlling the last mentioned valve.

90 35. In an automatic musical instrument, a set of tone elements, means providing a path for record controlled impulses, and connections to the set of tone elements, controlled by the impulses, said connections including a valve, means for alternately opening and closing the same by successive impulses and including a control valve for effecting the opening movement, a second control valve for effecting the closing movement and a pneumatically operated contact making device operated by the first mentioned valve and released by the second mentioned control valve.

105 36. In an automatic musical instrument, a set of tone elements, means providing a path for record controlled impulses, and connections to the set of tone elements, controlled by the impulses, said connections including a valve, means for alternately opening and closing the same by successive impulses and a contact closing means controlled by the valve.

37. In an automatic musical instrument, a set of tone elements, means providing a path for record controlled impulses, and connections to the set of tone elements, controlled by the impulses, said connections including a valve, means for alternately opening and closing the same by successive impulses, said last named means comprising a longitudinally and laterally movable member, pneumatically controlled means for moving the same longitudinally and pneumatically controlled means for moving the same laterally, control valve means for initiating the opening movement of the first valve when operated by the movable member when in one lateral position and control valve means for initiating the closing movement of the first valve when operated by the movable member when in its other lateral position.
38. In an automatic musical instrument, a set of tone elements, means providing a path for record controlled impulses, and connections to the set of tone elements, controlled by the impulses, said connections including a valve, means for alternately opening and closing the same by successive impulses, the said opening and closing means comprising a single longitudinally and transversely movable member, and pneumatic mechanism to alternately move the member longitudinally and laterally as the successive impulses occur.
39. In an automatic musical instrument, a set of tone elements, means providing a path for record controlled impulses, and connections to the set of tone elements, controlled by the impulses, said connections including a valve, means for alternately opening and closing the same by successive impulses and including a valve for effecting the opening movement, a second control valve for effecting the closing movement, a single member for alternately engaging the control valves, pneumatically operated means and locking means for holding the single member in locked engagement with one of the control valves until the end of the impulse and placing it in position to engage the other control valve as soon as the impulse is ended.
40. In an automatic musical instrument, a set of tone elements, means providing a path for record controlled impulses, and connections to the set of tone elements, controlled by the impulses, said connections including a valve, and mechanism for alternately opening and closing the same by successive impulses, including control valves for initiating the opening and closing of said valve, a pneumatic for opening the control valves and a pneumatic-spring means for causing the opening of the control valves to occur successively.
41. In an automatic musical instrument, a plurality of sets of tone elements, means providing a common path for record controlled impulses of different characteristics, control means functionally responsive to the impulses of different characteristics, respectively, and connections between the control means and the sets of tone elements, respectively, each connection including a valve and means for opening the valve and locking it in open position under control of one impulse imparted to the corresponding control means and releasing it under control of a succeeding impulse imparted to said control means.
42. In an automatic musical instrument, a plurality of sets of tone elements, means providing a common path for record controlled impulses of different characteristics, control means functionally responsive to the impulses of different characteristics respectively, said control means comprising pneumatics having different capacities, connections between the control means and the sets of tone elements respectively, each connection including a valve and means for opening the valve under control of one impulse imparted to the corresponding control means and closing it under control of a succeeding impulse imparted to said control means.
43. In an automatic musical instrument, a plurality of sets of tone elements, means providing a common path for record controlled impulses of different characteristics, control means functionally responsive to the impulses of different characteristics, respectively, said control means comprising pneumatics of different collapsing speed, connections between the control means and the sets of tone elements respectively, each connection including a valve and means for opening the valve under control of one impulse imparted to the corresponding control means and closing it under control of a succeeding impulse imparted to said control means.
44. In an automatic musical instrument, a plurality of sets of tone elements, means providing a common path for record controlled impulses of different characteristics, control means functionally responsive to the impulses of different characteristics, respectively, said control means comprising movable means having devices for closing a circuit at the end of their respective movements and having different rates of speed in movement respectively, connections between the control means and the sets of tone elements respectively, each connection including a valve and means for opening the valve under control of one impulse imparted to the corresponding control means and closing it under control of a succeeding impulse imparted to said control means.
45. In an automatic musical instrument,

a plurality of sets of tone elements, means providing a common path for record controlled impulses of different characteristics, control means functionally responsive to the impulses of different characteristics, respectively, said control means comprising movable means having adjustable devices for controlling the relative speed between the respective movable means, connections 10 between the control means and the sets of tone elements respectively, each connection including a valve and means for opening the valve under control of one impulse imparted to the corresponding control means and closing it under control of a succeeding impulse 15 imparted to said control means.

46. In an automatic musical instrument, a plurality of sets of tone elements, means providing a common path for record controlled impulses of different characteristics, control means functionally responsive to the impulses of different characteristics, respectively, said control means comprising pneumatics having different rates of speed in 20 collapse and means for controlling the supply of tension to one of the pneumatics whereby the relative speed between the two pneumatics is controlled, connections between the control means and the sets of tone 25 elements respectively, each connection including a valve and means for opening the valve under control of one impulse imparted to the corresponding control means and closing it under control of a succeeding impulse 30 imparted to said control means.

47. In an automatic musical instrument, a plurality of sets of tone elements, means providing a common path for record controlled impulses of different characteristics, primary circuit closing means controlled by 40 the impulses of different characteristics, respectively, secondary circuit closing means, connections between the latter means and the sets of tone elements, respectively, and connections between the primary circuit 45 closing means and the secondary circuit closing means, including pneumatically operable valves having connection with the secondary circuit closing means to control 50 the operation of the latter, respectively, and also including means for locking said valves into operative position with respect to the secondary circuit closing means upon one 55 operation of the corresponding primary circuit closing means and releasing it upon a succeeding operation thereof, whereby the secondary circuit closing means are operated to make and break the corresponding circuits by successive impulses imparted to the 60 primary circuit closing means and are maintained in operative relation with the corresponding sets of tone elements throughout the interim between said successive impulses.

48. In an automatic musical instrument,

a plurality of sets of tone elements, means 65 providing a common path for record controlled impulses of different characteristics, control members functionally responsive to the impulses of different characteristics respectively, valves respectively controlled 70 by the control members, connections between the control members and the respective valves, to open and lock the latter in one operation of the corresponding control member and release it in the next operation 75 thereof, controlling devices for the sets of tone elements and control connections between the sets controlling devices and the first-mentioned valves, respectively.

49. In an automatic musical instrument, a plurality of sets of tone elements, means providing a common path for record controlled impulses of different characteristics, operating means functionally responsive to the impulses of different characteristics respectively, valves respectively controlled by the operating means, connections between the operating means and the respective valves to open and lock the latter in one 80 operation of the corresponding operating means and release it in the next operation thereof, controlling devices for the sets of tone elements and pneumato-electric control 85 connections between the sets controlling devices and the first mentioned valves respectively.

50. In an automatic musical instrument, a plurality of sets of tone elements, means providing a common path for record controlled impulses of different characteristics, control members functionally responsive to the impulses of different characteristics respectively, valves respectively controlled by the control members, connections between the control members and the respective valves, to open and lock the latter in one 90 operation of the corresponding control member and release it in the next operation thereof, controlling devices for the sets of tone elements and pneumato-electric control 95 connections between the sets controlling devices and the first mentioned valves respectively.

51. In an automatic musical instrument, a plurality of sets of tone elements, means providing a common path for record controlled impulses of different characteristics, control members functionally responsive to the impulses of different characteristics respectively, valves respectively controlled by the control members, connections between the control members and the respective valves to open and lock the latter in one 100 operation of the corresponding control member and release it in the next operation thereof, controlling devices for the sets of tone elements, connections comprising a 105 motor pneumatic directly in control of the first mentioned valves, and electro-pneumatic operating means for a set controlling device and controlled by the motor pneumatic.

115

120

125

elements and control connections between said sets controlling devices and valves respectively, comprising contact making pneumatics operatively controlled by said 5 valves, and electro-magnetic control means for the sets controlling devices, controlled by the contact making pneumatics.

52. In an automatic musical instrument, a plurality of sets of tone elements, means 10 providing a common path for record controlled impulses of different characteristics, control members functionally responsive to the impulses of different characteristics respectively, valves respectively controlled by 15 the control members, connections between the control members and the respective valves, said connections including oscillating control members and means during one operation to place the same in position to 20 cause the reverse action of the said valves in the next operation, sets controlling devices and control connections between said devices and valves, respectively.

53. In an automatic musical instrument, a 25 plurality of sets of tone elements, means providing a common path for record controlled impulses of different characteristics, control members functionally responsive to the impulses of different characteristics respectively, valves respectively controlled by 30 the control members, connections between the control members and the respective valves, said connections including oscillating valve control members and pneumatic 35 means, during one operation to place the same in position to cause the reverse action of the said valves in the next operation, sets controlling devices, and control connections between said devices and valves, 40 respectively.

54. In an automatic musical instrument, a plurality of sets of tone elements, means 45 providing a common path for record controlled impulses of different characteristics, control members functionally responsive to the impulses of different characteristics respectively, valves respectively controlled by 50 the control members, connections between the control members and the respective valves, said connections including oscillating control members and spring-pneumatic 55 means under control of the valve during each operation to place the control members in position to cause the reverse action of the valves in the succeeding operation, sets controlling devices and control connections between the sets controlling devices and valves, respectively.

55. In an automatic musical instrument, 60 a plurality of sets of tone elements, means providing a common path for record controlled impulses of different characteristics, control members functionally responsive to the impulses of different characteristics re-

spectively, valves respectively controlled by 65 the control members, connections between the control member and the respective valves, said connections including a longitudinally movable and oscillating control member and spring-pneumatic means under control of 70 the valves during each operation to place the control members in position to cause the reverse action of the valves in the next operation, sets controlling devices and control connections between said devices and valves, 75 respectively.

56. In an automatic musical instrument, a plurality of sets of tone producing elements, a plurality of devices, respectively for controlling the speaking of notes within said sets, a single record controlled element for controlling said plurality of devices, connections between the record controlled element and devices for operating one or more of the devices, said connections comprising 80 slow acting and quick acting means.

57. In an automatic musical instrument, a plurality of sets of tone producing elements, a plurality of devices, respectively for controlling the speaking of notes within said sets, a single record controlled element for controlling said plurality of devices, connections between the record controlled element and devices for operating one or more of the devices, said connections comprising 85 slow acting and quick acting pneumatics.

58. In an automatic musical instrument, a plurality of sets of tone producing elements, a plurality of devices, respectively for controlling the speaking of notes within said sets, a single record controlled element for controlling said plurality of devices, connections between the record controlled element and devices for operating one or more of the devices, said connections comprising 100 slow and quick acting means, and mechanisms operated respectively by the slow and quick acting means to operate the respective devices.

59. In an automatic musical instrument, 110 a plurality of sets of tone producing elements, a plurality of devices, respectively for controlling the speaking of notes within said sets, a single record controlled element for controlling said plurality of devices, and connections between the record controlled element and devices for operating one or more of the devices, said connections comprising 115 slow and quick acting means, mechanisms, including valves, operated respectively by the slow and quick acting means and means controlled by the respective mechanisms to cause the respective devices to be returned to normal position upon a second operation of the quick acting or slow acting mechanism.

60. In an automatic musical instrument, 120 a plurality of sets of tone producing ele-

- ments, a plurality of devices, respectively for controlling the speaking of notes within said sets, a single record controlled element for controlling said plurality of devices, 5 connections between the record controlled element and devices for operating one or more of the devices, said connections comprising slow and quick acting pneumatics, and mechanisms operated respectively by the slow and quick acting pneumatics to operate the respective devices.
61. In an automatic musical instrument, a plurality of sets of tone producing elements, a plurality of devices, respectively for controlling the speaking of notes within said sets, a single record controlled element for controlling said plurality of devices, connections between the record controlled element and devices for operating one or 15 more of the devices, said connections comprising slow and quick acting pneumatics, mechanisms operated respectively by the slow and quick acting means to operate the respective devices and elements connected 20 to the respective mechanisms to cause the respective devices to be returned to normal position upon a second operation of the quick acting or slow acting mechanism.
62. In an automatic musical instrument, a plurality of elements for controlling sets of playing notes, a single record controlled element and connections between the record controlled element and set controlling elements whereby impulses imparted to said 30 single element will cause either or both of said set controlling elements to operate.
63. In an automatic musical instrument, a plurality of elements for controlling sets of playing notes, a single record controlled 40 element and connections between the record controlled element and set controlling elements whereby impulses imparted to said single element will cause either or both of said set controlling elements to operate, said 45 connections comprising slow acting and quick acting means.
64. In an automatic musical instrument, a plurality of elements for controlling sets of playing notes, a single record controlled 50 element and connections between the record controlled element and set controlling elements whereby impulses imparted to said single element will cause either or both of said set controlling elements to operate, said 55 connections comprising slow acting and quick acting pneumatics.
65. In an automatic musical instrument, a plurality of elements for controlling sets of playing notes, a single record controlled 60 element and connections between the record controlled element and set controlling elements whereby impulses imparted to said single element will cause either or both of said set controlling elements to operate, said 65 connections comprising slow acting and quick acting means, and mechanisms operated respectively by the slow and quick acting means to actuate the respective set controlling elements.
66. In an automatic musical instrument, a plurality of elements for controlling sets of playing notes, a single record controlled element and connections between the record controlled element and set controlling elements whereby impulses imparted to said 70 single element will cause either or both of said set controlling elements to operate, said connections comprising slow acting and quick acting pneumatics and mechanisms operated respectively by the slow and quick acting 75 means to actuate the respective set controlling elements.
67. In an automatic musical instrument, a plurality of elements for controlling sets of playing notes, a single record controlled 80 element, connections between the record controlled element and set controlling elements whereby impulses imparted to said single element will cause either or both of said set controlling elements to operate, said connections comprising slow acting and quick acting 85 means and mechanisms operated respectively by the slow and quick acting means to actuate the respective set controlling elements, and means connected to the respective mechanisms to cause the set controlling elements to return to normal position upon subsequent operation of the quick acting or slow acting mechanism.
68. In an automatic musical instrument, a plurality of elements for controlling sets of playing notes, a single record controlled element, connections between the record controlled element and set controlling elements whereby impulses imparted to said single 90 element will cause either or both of said set controlling elements to operate, said connections comprising slow acting and quick acting means and mechanisms operated respectively by the slow and quick acting 95 means to actuate the respective set controlling elements, and means connected to the respective mechanisms to cause the set controlling elements to return to normal position upon subsequent operation of the quick acting or slow acting mechanism.
69. In a musical instrument a motor pneumatic, a swinging member pivotally connected thereto to move in a direction substantially longitudinally of the direction of extension of the member, a second motor pneumatic connected to said member to move the same pivotally about its connection to the first named pneumatic and means for applying pneumatic tension to said 100 pneumatics to move the same.
70. In a musical instrument a motor pneumatic, a swinging member pivotally connected thereto to move in a direction substantially longitudinally of the direction of 105

- extension of the member, a second motor pneumatic connected to said member to move the same pivotally about its connection to the first named pneumatic, means for applying pneumatic tension to said pneumatics, means for preventing the operation of the second named pneumatic when tension is first applied and means for rendering inoperative the preventing means and rendering operative the second named pneumatic to move the rod.
71. In a musical instrument, a motor pneumatic, a swinging member pivotally connected thereto to move in a direction substantially longitudinally of the direction of extension of the member, a second motor pneumatic connected to said member to move the same pivotally about its connection to the first named pneumatic, and means for applying pneumatic tension to said pneumatics in the order named.
72. In a musical instrument, a motor pneumatic, a swinging member pivotally connected thereto to move in a direction substantially longitudinally of the direction of extension of the member, a second motor pneumatic connected to said member to move the same pivotally about its connection to the first named pneumatic, means for applying pneumatic tension to said first named pneumatic, and means operated by the swinging member to apply tension to the second named pneumatic.
73. In a musical instrument, a motor pneumatic, a swinging member pivotally connected thereto to move in a direction substantially longitudinally of the direction of extension of the member, a second motor pneumatic connected to said member to move the same pivotally about its connection to the first named pneumatic, means for applying pneumatic tension to said first named pneumatic, means operated by the movement of the swinging member to apply tension to the second named pneumatic, and a locking device for preventing the second named pneumatic from operating.
74. In a musical instrument, a motor pneumatic, a swinging member pivotally connected thereto to move in a direction substantially longitudinally of the direction of extension of the member, a second motor pneumatic connected to said member to move the same pivotally about its connection to the first named pneumatic, means for applying pneumatic tension to said first named pneumatic, means operated by the movement of the swinging member to apply tension to the second named pneumatic, a locking means for preventing the second named pneumatic from operating and connections for releasing the locking means thereby permitting the second named pneumatic to move the member.
75. In a musical instrument two controlling devices, means for alternately operating the controlling devices, a motor for moving the operating means, a second motor for placing the operating means under tension and locking means for preventing the operating means from moving under influence of the second motor.
76. In a musical instrument two controlling devices, means for alternately operating the controlling devices, a single record controlled element, pneumatic means controlled by the operating means during one stroke for setting the same in position to operate the other controlling device on the next stroke.
77. In an automatic musical instrument, a wind chest provided with a plurality of channels, a set of tone elements operatively related to each channel, a valve for each channel, means providing a common path for record controlled impulses of different characteristics, means functionally responsive to the impulses of different characteristics respectively, and connections between the latter means and the valves, respectively, to operate either valve alone or both valves together.
78. In an automatic musical instrument, a wind chest provided with a plurality of channels, a set of tone elements operatively related to each channel, a valve for each channel, means providing a common path for record controlled impulses of different characteristics, a plurality of control members connected to said means and provided with elements which are functionally responsive to the impulses of different characteristics respectively, and operative connections between said element and the valves, respectively.
79. In an automatic musical instrument, a wind chest provided with a plurality of channels, a set of tone elements operatively related to each channel, a valve for each channel, means providing a common path for record controlled pneumatic impulses of different characteristics, means functionally responsive to the impulses of different characteristics respectively, and operative connections between the latter means and the valves respectively, to operate either valve alone or both valves together.
80. In an automatic musical instrument, a wind chest provided with a plurality of channels, a set of tone elements operatively related to each channel, a valve for each channel, means providing a common path for record controlled impulses of different characteristics, and mechanism to operate either valve alone or both together, including circuit making and breaking means functionally responsive to the impulses of different characteristics, respectively, and operative connections between the latter means and the valves.
81. In an automatic musical instrument,

- a wind chest provided with a plurality of channels, a set of tone elements operatively related to each channel, a valve for each channel, means providing a common path 5 for record controlled pneumatic impulses of different characteristics, a plurality of pneumatics functionally responsive to the impulses of different characteristics, respectively, circuit making and breaking means 10 controlled by the pneumatics, respectively and operative connections between the latter means and the valves.
82. In an automatic musical instrument, a wind chest provided with a plurality of 15 channels, a set of tone elements operatively related to each channel, means providing a common path for record controlled impulses of different lengths, circuit making and breaking means functionally responsive to the impulses of different lengths, respectively, and operative connections between the latter means and the valves, respectively. 20
83. In an automatic musical instrument, a wind chest provided with a plurality of channels, a set of tone elements operatively related to each channel, means providing a common path for record controlled pneumatic impulses of different lengths, pneumatically operable circuit making and breaking means functionally responsive to the impulses of different lengths, respectively, and operative connections between the latter means and the valves, respectively. 25
- 30

GEO. W. GITTINS,
Administrator of the estate of Heinrich Bockisch, inventor, deceased.
